CLAIM

Jar, as disclosed and shown in the accompanying drawings.

DESCRIPTION

FIG. 1 shows a perspective view of a jar showing my new design;

FIG. 2 shows a top perspective view thereof, shown in an open position;

FIG. 3 is a front elevation view thereof;

FIG. 4 is a left side elevation view thereof;

FIG. 5 is a rear elevation view thereof;

FIG. 6 is a right side elevation view thereof;

FIG. 7 is a top plan view thereof;

FIG. 8 is a bottom plan view thereof; and,

FIG. 9 is a cross-section view taken along the lines 9—9 in FIG. 7, the outer sidewall details that should be seen through the transparent material of the jar have not been shown for ease of illustration.

The broken line showing of the thread portion of the jar pour spout illustrates environmental structure and forms no part of the claim.
